UNITED STATES PATENT OFFICE

2,150,556

COMBINED SHIP'S BITT AND VENTILATOR

Peter Frederick Leon, Oranjestad, Aruba,
Dutch West Indies

Application November 28, 1936, Serial No. 113,181

9 Claims. (Cl. 114—211)

My invention relates to improvements in means for use as a ventilator and a cable attaching bitt or part for ships, boats and the like, and the same has for its object to provide a simple, durable and efficient device which may be readily opened for use as a ventilator or closed against the access of water during storms or heavy seas.

Further, said invention has for its object to provide a device of the character specified in which the parts thereof may be readily extended or collapsed in order to open or close the ventilator.

Further, said invention has for its object to provide a device of the character specified in which one of the parts thereof constituting the bitt or post is of tubular construction forming a portion of the ventilator passage extending through the deck and serving as a housing for other parts of the ventilator.

Further, said invention has for its object to provide a device of the character specified in which the ventilator includes telescoping parts having actuating means for controlling the relative position of the parts.

Further, said invention has for its object to provide a device of the character specified in which the actuated part of the ventilator carries a closure for effectively sealing the fixed member or housing constituting the bitt in the closed position of the ventilator.

Further, said invention has for its object to provide a device of the character specified in which the extensible member of the ventilator has an opening in the wall thereof including a socket for the attachment of a mouth member constituting a ventilator cowl or hood adapted to be readily removed when the ventilator is to be closed.

Further, said invention has for its object to provide a device of the character specified in which a sheet metal member or jacket secured to the deck and embracing and connecting contiguous posts or bitts at points above the deck serves to bind the said posts together and to brace the same, whereby to supplement the post anchorages in the deck in resisting stresses and strains imposed upon the posts by the ropes and cables.

Further, said invention has for its object to provide a device of the character specified in which an insect screen may be employed without interfering with the operation of the device.

Other objects will be in part be obvious and in part be pointed out hereinafter.

To the attainment of the aforesaid objects and

ends my invention consists in the novel features of construction, and in the combination, connection and arrangement of parts hereinafter more fully described and then pointed out in the

5

In the accompanying drawings—

Figure 1 is a side elevation of one form of device constructed according to and embodying my said invention;

Fig. 2 is a plan thereof;

Fig. 3 is an enlarged cross-section thereof on the line 3—3 of Fig. 2;

Fig. 4 is a similar cross-section showing the parts in extended position with the removable cowl in position thereon;

Fig. 5 is a cross-section on the line 5—5 of Fig. 4;

Fig. 6 is a perspective of one of the ventilator cowls or hoods, and

Fig. 7 is a perspective of the screen.

Referring to the drawings, the deck or floor of the ship or other structure, indicated at 10, is provided with openings 11 therethrough receiving like devices 12 and 12^a each constituting a combined ventilator and bitt embodying the invention.

Each of the devices 12, 12^a comprises a tubular member 13, preferably composed of cast iron or other metal having openings 14 and 15 at the ends thereof, and being of sufficient strength and size 30 to function as a post or bitt for the attachment or securing of the usual cables or ropes employed on shipboard. Each of the members 13 is secured within its opening 11 by means, such as the flanged rings 16 secured to the opposite faces 35 of the deck and to the member 13 by bolts or other securing means 17. The member 13 forms a ventilator passage or conduit providing communication between the outside and the spaces below deck.

The thickened upper margin 18 of the post member 13 is provided with an annular groove or recess 19 in the top thereof adapted to receive the cooperating annular rib 20 upon the inner side of the metal cover 21 in the closed position 45 thereof as hereinafter described. A transversely disposed spider 22 is secured within the member 13 near the lower end thereof, and is provided centrally thereof with hub portion or bushing 23, preferably of bronze, constituting a threaded nut 50 cooperating with a threaded spindle or shaft 24, also preferably of bronze, secured or swiveled at the upper end thereof to the cover 21. If so desired, a member 26 of teakwood or other material may be also secured to the top of the metal 55

cover 21 by means of the screw 25 to allow the device to be used as a seat in the closed position of the ventilator.

The cover 21 also serves as a support for the tubular ventilator member 27, composed preferably of sheet metal to minimize the weight to be lifted, and welded or otherwise secured at one end to the depending annular rib 28 upon the inner side of the cover 21 which also forms a closure for the outer end of the member 27. The member 27 is telescopically received within the fixed member 13 which serves as a housing therefor and for the spindle 24 in the closed position of the ventilator, and said member 27 when extended, as shown in Fig. 4, communicates through the open lower end 29 thereof with the passage in the member 13. The telescoping part 27 may be readily extended or collapsed by rotation of the actuating wheel 30 secured to the lower end 29 of the screw spindle 24 below deck. In the closed position of the device the parts 19 and 20 interengage to effectively seal the ventilator against access of water. A suitable packing may also be employed therebetween.

Air is admitted to the member 27 in the extended position thereof through a preferably polygonal opening 31 in the wall thereof. The member 27 is provided with inwardly directed flanges 32 disposed about the margin of said opening 31 and forming a socket for detachably receiving the mouth member or ventilator cowl 33, preferably formed of sheet metal. The member 33 has a neck portion 34 corresponding in shape with the socket 32 and adapted to fit the same and a flaring inlet or mouth portion 35. When two or more of the ventilators 12, 12^a are associated as shown, the cowls 33 may be made slightly different in size so that they may be nested together when not in use.

It is often desirable to provide means for preventing insects from entering the ship through the ventilating device, and for this purpose I provide the circular screen 36 having the surrounding frame 37 and a reinforced opening 38 in the middle thereof. The screen 36 is of a size adapted to fit the interior of the tubular member 13, and the opening 38 is adapted to receive and fit the lower end of the spindle 24 below the spider 22. The screen 36 is retained in place by the handle 39 which is removably secured to the spindle by a screw 30^a.

In operation, when the ventilator is closed, the screen member rests upon the inturned flange 39 at the lower end of the member 13. When the ventilator is opened the screen 36 is engaged by the member 30 and moves up with the screw so as to screen the passage without interfering with the opening operation.

When the devices 12, 12^a are employed in pairs, I preferably provide means 40 for reinforcing, bracing and connecting the projecting portions of the members 13 at points above their anchorages in the deck. Said means preferably comprises a sheet metal jacket 41, either in one or two parts, including a transverse intermediate portion 42 having openings 43 therein for receiving the members 13 and the downwardly extending lateral portions 44 terminating in feet 45 in engagement with the deck 10 and secured thereto by the bolts or other securing means 46. For purposes of assembly, the jacket 41 may, if so desired, be made in two cooperating parts 41^a, 41^b having the downwardly directed flanges 47 thereon extending longitudinally of the edges at 75 the central juncture line 48 thereof. The two

parts 41^a and 41^b are secured together at the flanges 47 by the bolts or other securing means 49. By securing the jacket parts together at points below the top 42 thereof provides a smooth surface at the top of the jacket 41 and between and around the posts 12, 12^a obviating rough or projecting portions at the top liable to cut or fray the ropes or cables.

By my invention I provide a strong, durable device capable of being employed as a post or bitt 10 for the attachment of cables, etc. and as a ventilator which may be readily opened and closed, and which in the closed position thereof effectively keeps out the water, and serves to house the extensible part thereof.

Having thus described my said invention what I claim and desire to secure by Letters Patent is:

1. A device of the character described comprising a fixed tubular member, an extensible tubular member associated therewith, a support 20 within said fixed member below said extensible member, a screw threaded in said support and connected to said extensible member, a screen disposed transversely within said fixed member below said support, means mounting said screen 25 on said screw for movement therewith and relative thereto, and means on the lower end of said fixed member for supporting said screen in the closed position of the device.

2. A device of the character described comprising a pair of tubular members extending through the deck of a ship and constituting cooperating bitts, rings secured to the opposite faces of said deck in engagement with said tubular members for securing the same in position, 30 and a sheet metal member having openings therein receiving said members and including downwardly directed lateral portions secured to the deck.

3. A device of the character described comprising a pair of tubular members extending through and anchored within the deck of a ship and constituting cooperating bitts, a member including a transverse portion having openings therein receiving said tubular members and downwardly directed lateral portions secured to the deck, and means for securing said last-named member about said openings to said tubular members.

4. A device of the character described comprising a metallic tubular member constituting a bitt adapted to be secured to the floor or deck of a ship about an opening therein and extending thereabove, a metallic closure for the top of said member engageable with the upper edge 55 thereof in the closed position of the closure, said closure and said edge including interengaging means cooperating to form a seal, and said closure having a depending flange formed integrally therewith at the inner side thereof inwardly of 60 the margin, a relatively lighter, tubular member depending from said flange and telescoping said first named member, said last named member having a ventilating opening in the wall thereof exposed in the extended position of said last 65 named member, and means operating within said first named member and connected to said closure for actuating said closure and said depending member.

5. A device of the character described comprising a tubular member constituting a bitt adapted to be secured to the floor or deck of a ship about an opening therein and extending thereabove, a closure for the top of said member engageable with the upper edge thereof in the 75

closed position of the closure to form a seal, a tubular member depending from said closure inwardly of the marginal portion thereof and telescoping said first named member, said last-named member having an opening in the wall thereof including an inwardly directed socket, means disposed within said first named member for actuating said closure and said depending member to extend the same and close the same, and a cowl member adapted to be detachably received within said socketed opening in the extended position of the parts.

6. A device of the character described comprising an open-ended tubular member constituting a bitt adapted to be secured to the floor or deck of a ship about an opening in said deck and extending thereabove, a closure for the top of said tubular member engageable with the upper edge thereof in the closed position of the closure to form a seal, a tubular member depending from said closure inwardly of the margin thereof and telescoping said first-named member, said depending member having an opening in the wall thereof exposed for ventilation in the projected position of said depending member, a cowl member detachably secured to said depending member at said opening in the projected position of said depending member for removal to allow movement of said closure and said depending member to closed position, and means for moving the last-named parts to closed or open positions.

7. A device of the character described comprising an open-ended, cast metal tubular member constituting a bitt adapted to be secured to the floor or deck of a ship about an opening in said deck and extending thereabove, a closure of like metal having attaching means formed integrally therewith and depending from said closure inwardly of the margin thereof, the upper edge of said tubular member and the margin of said closure having means engaging each other to form a seal in the closed portion, a sheet metal tubular member secured at its upper end to said attaching means in position to depend from the closure and telescope said first-named

member, said sheet metal member having an opening in the wall thereof adapted to be exposed in the projected position of said sheet metal member for ventilating purposes, and means housed within said tubular members and connected directly with said closure for actuating the same.

8. A device of the character described comprising an open-ended tubular member constituting a bitt adapted to be secured to the floor or deck of a ship about an opening in said deck, a closure for the top of said tubular member engageable with the upper edge thereof, a tubular member depending from said closure inwardly of the margin thereof and telescoping said first-named member, said depending member having an opening in the wall thereof for ventilation, a support secured within said first-named member below said depending member in the closed position thereof, an actuating member extending through and working in said support and connected to said closure, a screen member slidably mounted on said actuating member below said support transversely within said first-named member, and manipulating means at the lower end of said actuating member for retaining said screen member in place thereon.

9. A device of the character described comprising an open-ended tubular member constituting a ship's bitt, a closure for the top of said tubular member having a tubular member depending from said closure and telescoping said first-named member, said depending member having an opening in the wall thereof for ventilation in the projected position of said member, a support secured within said first-named member below said depending member in the closed position thereof, a screw working in said support and connected to said closure, a screen member below said support having a central opening therein for receiving said screw, and actuating means at the lower end of the screw for retaining said screen member in place thereon.

PETER FREDERICK LEON. 45
